UNITED STATES PATENT OFFICE.

DUDLEY T. FISHER, OF COLUMBUS, OHIO, ASSIGNOR TO THE JEFFREY MANUFACTURING COMPANY, A CORPORATION OF OHIO.

CABLE-WINDING MECHANISM FOR LOCOMOTIVES.

1,113,975.

Specification of Letters Patent.

Patented Oct. 20, 1914.

Original application filed September 20, 1907, Serial No. 393,829. Divided and this application filed November 10, 1911. Serial No. 659,629.

To all whom it may concern:

Be it known that I, DUDLEY T. FISHER, a citizen of the United States, residing at Columbus, in the county of Franklin and State 5 of Ohio, have invented certain new and useful Improvements in Cable-Winding Mechanisms for Locomotives, of which the following is a specification, reference being had therein to the accompanying drawing.

10 This invention relates to winding mechanisms and more especially to winding mechanisms adapted for use upon electric mine locomotives for hauling cars to the locomotive from relatively remote points.

15 In coal mines relatively small cars are used which, while being loaded are separated from each other and scattered over more or less of the mine, one in one room or at one loading point and others at others.

20 The older plan, where animal power was used, was to haul each of these cars singly by an animal from the room, after it had been loaded, to a collecting point where a number of cars were coupled together to 25 form a train or "trip". Since the introduction of electric power, use has been made for this purpose of "gathering" locomotives, each having a reel with an electric cable thereon, the terminal of which can be 30 connected electrically to a current supplying wire, so that as the car moves away from the source of supply, the cable on the reel will maintain a continuity of electric connections to the motor. In using this apparatus the locomotive is itself run into the 35 rooms successively and coupled to the isolated loaded cars and thereafter hauls them to the gathering point. Under many circumstances these gathering locomotives with 40 cable reels cannot be used to advantage, particularly where the mine roof is low or where the track has been hastily constructed, as the branch tracks frequently are which extend from the entry into the room.

45 The present invention relates to an apparatus adapted to be attached to an ordinary locomotive and of such nature that the locomotive can remain in the entry or at some distant point and yet the loaded car can be 50 hauled by power toward it while it remains stationary.

Of the drawings Figure 1 is a top plan view of a locomotive having thereon a wind-

ing mechanism embodying my improvements. Fig. 2 is a side elevation of the locomotive. Fig. 3 is an end elevation taken looking toward the reel carrying end. Fig. 4 is a view showing the reel and the power transmitting devices in vertical central section and showing an electric motor conventionally by outline.

A indicates a car, an electric locomotive of the kind used in coal mines being selected for the purposes of illustration. Its wheels B are fitted to the track rails. Its body is formed of a heavy cast frame having the side parts C, C, and the end connecting parts D, D. Many of the parts of the car or locomotive are indicated conventionally by dotted lines. At E the electric motor is situated in the space between the two axles b, b', this motor being geared to one of the axles in any suitable way, and by preference the axles are geared together or connected by chains and sprockets. At F there is a chamber or space left for the motorman and for the parts which he is called upon to manipulate frequently, such as the wheel of the controller at G and the hand wheel of the brake mechanism at H.

At the end of the locomotive opposite to that where the motorman is placed I arrange a reel for the haulage cable. This is indicated by 1 and is mounted on a vertically arranged shaft or mast 2. This shaft is secured to a base or support 3 which is in the form of a strong bar extending across from one of the side elements C of the car body to the other, and firmly bolted thereto.

The mast 2 is fastened by a key 4 in this base in such way that it is held firm against rotation. The reel 1 can rotate loosely and freely around this shaft when it is disengaged from the other parts.

8 indicates an electric motor having a suitable field frame and connected to the upper end of the shaft 2 by means of the flange or plate 6 which is rigidly fastened to the shaft by a key at 7 and is firmly bolted to the motor frame.

9 indicates a relatively large spur gear wheel which is mounted upon the shaft 2. Between the reel and the shaft there is a lining or bearing 5, and between the wheel 9 and the shaft there is a lining 10. The linings are of such dimensions and so

shaped in relation to each other that the wheel 9 is held normally out of engagement or contact with the reel.

11 is a pinion engaging the driving wheel 9, this pinion being connected to the vertically arranged shaft 12 mounted in the bearing 15. At the upper end of the shaft there is a bevel wheel 13 which meshes with the bevel pinion 14 on the end of the armature shaft.

10 The reel can be detachably clutched to its driving mechanism by suitable devices.

17 is a sliding collar mounted on the hub 16 of the reel, this collar having a groove 15 for a shaft band 20 which is held against rotation but permits the collar to revolve within it.

18, 18 are clutch pins (of suitable number) secured to the collar 17 and passing 20 through apertures 19 in the web part of the reel. When the collar is slipped along the reel hub the pins 18 are thrust into engagement with the ratchet at 24 on the hub of the gear wheel 9.

25 The band or ring 20 is moved back and forth by a link and lever system comprising the links 21, each pivoted to the band and pivotally connected to a bell lever 22 which is mounted at 22^a on the base 3.

30 23 is an operating rod extending to the motorman's place, by which he can move the pins 18 at will and effect the clutching or unclutching of the reel.

The cable is indicated at 25. One end is 35 secured to the reel 1, and it may be of any suitable length. It may be taken off directly toward the front of the car, or laterally therefrom. Under most circumstances, however, I prefer to use the mechanism in 40 such way that the cable must extend longitudinally of the locomotive, backward. To permit this, I employ a roller guide, at 26, comprising horizontal rollers 26^a and vertical rollers 26^b. At the other end of the 45 locomotive are roller sheaves 27 and 28 supported by the bracket casting 29, which is secured to the rear cross end part D of the car. From these sheaves 27 and 28 the cable can be taken in any desired direction.

50 30 indicates a guard device, preferably formed as a casting and bolted to the base or support 3. It extends part way around the inner side of the reel, and serves to prevent any cable coils which may be lying 55 loosely around the reel from falling off of the edge.

At 31 and 32 there are ribs formed on the casting 3 and at the sides thereof for guiding the cable to the reel and also to prevent 60 the falling off of the coils; and to still further insure against the falling of the coils, and the proper guiding of the cable, angles 33 and 34 are fastened to the end cross bars of the car.

65 The master gear wheel 9 is formed with

a relatively large cavity or chamber 35 adapted to hold a body of lubricant which gradually passes therefrom to the wearing surfaces of the master wheel 9 and of the reel 1.

70 The manner of using an apparatus of the kind above described will be readily understood.

The locomotive is stopped in the mine entry in such position that the motorman can look through the passage-way or the "mouth" into the room. His assistant, the "trip rider," takes the end of the cable and carries it into the room and couples it to the car to be drawn out, the motorman having first by the draw-rod 23 and the sliding collar 20 withdrawn the clutch-pin 18 from the gearing thus allowing the cable to freely rotate. After the end of the cable is coupled to the car the motorman can, by means of the rod 23 and the collar 20, thrust the clutch pin 18 into engagement with the master wheel 9. He then starts the motor 8 and the reel is caused to wind up the cable and draw the car from the room to the track in the entry. When a loaded car is sufficiently close to the locomotive the latter is set in motion by means of its motor E and the loaded car is drawn to the point where the trains or "trips" of several cars are made up.

75 It will be seen that in many respects there can be departure from the details which I have designed in this particular construction without departing from the spirit of the essential features of the invention.

80 This application constitutes a division of my copending application for locomotives, filed Sept. 20, 1907, Ser. No. 393,829. Said application relates to the general arrangement of locomotive parts including the reel and other cable controlling devices. This present application relates primarily to the reel and to the parts immediately associated with it.

85 What I claim is:

1. In a winding mechanism, the combination of a reel mounted for rotation about a vertical axis, a motor mounted above the reel with its axis horizontal and intersecting the reel axis, a gear wheel mounted coaxially with the reel between it and the motor, a power transmitting connection between the gear wheel and the reel, a vertical power shaft, a pinion on the power shaft meshing with the gear wheel and gearing between the power shaft and the motor, the said motor being operable independently of all parts except the said power transmitting elements and the reel.

120 2. In a winding mechanism, the combination of a reel mounted for rotation about a vertical axis, a motor mounted above the reel with its axis horizontal and intersecting the reel axis, a spur gear wheel mounted

co-axially with the reel between it and the motor, a manually controllable clutch between the gear wheel and the reel, a vertical power shaft, a pinion at the lower end of the shaft meshing with the spur gear wheel, and gearing between the upper end of the power shaft and the motor, the said motor being operable independently of all parts except the said power transmitting elements 10 and the reel.

3. In a winding mechanism, the combination of a reel mounted for rotation about a vertical axis, a motor mounted above the reel with its axis horizontal and intersected by the reel axis, a gear wheel mounted between the reel and the motor for rotation co-axially with the reel, a manually controllable clutch between the gear wheel and the reel, and gearing between the gear wheel 15 and the motor, the said motor being operable independently of all parts except the said power transmitting elements and the reel.

4. In a winding mechanism, the combination of a reel provided with a hub having an apertured web, a gear wheel mounted for rotation concentrically with the reel and provided with notches at points adjacent the apertures of the web, means for applying 25 power to the gear wheel to rotate it, and a manually controllable clutch device comprising a plurality of pins adapted to extend through the apertures of the web and engage the notches of the gear wheel.

35 5. In a winding mechanism, the combination of a reel mounted for rotation about a vertical axis, a stationary vertical mast upon which the reel has a bearing, a gear wheel mounted above the reel and having a bearing on the said mast, the said gear wheel being provided with an oil reservoir and with ducts leading from the oil reservoir to the said mast, a power connection between the gear wheel and the reel, and 45 means for applying power to the gear wheel to rotate it.

6. In a winding mechanism, the combination of a base, a vertical mast having its lower end secured to the base, a reel having a bearing on the mast, a gear wheel above the reel and rotatable independently thereof, the said gear wheel also having a bearing on the mast, a manually controllable clutch between the gear wheel and the reel, a motor 50 supported on the mast at its upper end, and gearing between the gear wheel and the motor, the said motor being operable independently of all parts except the said power transmitting elements and the reel.

60 7. In a winding mechanism, the combination of a base, a mast secured at its lower end to the base, a reel having a bearing on

the mast, a gear wheel rotatable with the reel, means for operably connecting the gear wheel to the reel, a motor mounted on the mast at its upper end, a vertical power shaft, a support for the said vertical power shaft secured to the motor frame, a pinion at the lower end of the vertical power shaft meshing with the said gear wheel and gearing 65 between the motor and the upper end of the said vertical power shaft.

8. In a winding mechanism, the combination of a base, a vertical mast having its lower end secured to the base, a reel having a bearing on the mast, a gear wheel above the reel and rotatable independently thereof, the said gear wheel also having a bearing on the mast, a manually controllable clutch between the gear wheel and the reel, and 70 power means for driving the gear wheel.

9. In a winding mechanism, the combination of a support, a reel mounted on the support for rotation about a vertical axis, means for driving the reel, and a stationary vertical flange mounted on the support adjacent the lower flange of the reel and extending upward therefrom along a part of its periphery. 85

10. In a winding mechanism, the combination of a support, a reel mounted on the support for rotation about a vertical axis, means for driving the reel, and two stationary walls mounted upon the support and extending downward from the periphery of 90 the lower flange of the reel at diametrically opposite points. 95

11. In a winding mechanism, the combination of a support, a reel mounted on the support for rotation about a vertical axis, 100 means for driving the reel, and downward and outward inclined cable guides mounted on the support and alining at their upper ends with the periphery of the lower flange of the reel. 105

12. In a winding mechanism, the combination of a reel mounted for rotation about a vertical axis, means for driving the reel, a stationary flange adjacent the lower flange of the reel and extending upward therefrom 110 along a part of its periphery, two stationary flanges extending downward from the periphery of the reel at diametrically opposite points, and downward and outward inclined cable guides and supports alining at their 115 upper ends with the periphery of the lower flange of the reel.

In testimony whereof I affix my signature, in presence of two witnesses.
